UNITED STATES PATENT OFFICE.

JOHN T. GAINES, OF INDIANAPOLIS, INDIANA.

ART STAND LAMP.

Application filed June 12, 1922. Serial No. 567,791.

To all whom it may concern:

Be it known that I, JOHN T. GAINES, a citizen of the United States, residing at Indianapolis, in the county of Marion and State of Indiana, have invented a new and useful Art Stand Lamp, of which the following is a specification, reference being had to the accompanying drawings and to the letters and figures of reference marked thereon.

This invention relates to a portable art stand lamp and has reference more particularly to a stand lamp column that is principally of monolithic formation and having highly polished face portions of irregular design.

An object of the invention is to provide an art stand lamp of such type as to permit different lamps to be ornamentally different and without materially affecting the cost of production, so that the purchaser of each lamp may have an exclusively original design of surface ornamentation differing from that of every other lamp, which lamp may be of such height as to be adapted to stand upon a table, or taller to stand upon a floor.

Another object is to provide an art stand lamp which shall be of such construction as to have differently colored and polished face portions so disposed as to be exposed to slanting rays of light, more particularly from electrical or gas lights on the lamp structure, in order that the lamp shall be novel in appearance and pleasing to the observer.

A further object is to provide an improved art stand lamp which shall permit of monolithic concrete construction at moderate cost, in order that it shall be sufficiently heavy to stand firmly, shall not be liable to serious damage in case of accident thereto, which may be adapted for electrical lighting or for gas lighting, and which shall be durable and economical in use.

With the above mentioned and other objects in view, the invention consists in an art stand lamp having a novel composite column and lamps mounted in a novel manner thereon; and, the invention consists also further in the parts and combinations and arrangements of parts as hereinafter particularly described and further set forth in the accompanying claims.

Referring to the drawings, Figure 1 is a fragmentary perspective view of a table

and a lamp thereon constructed substantially in accordance with the invention; Fig. 2 is an elevation showing the principal part of the lamp column; Fig. 3 is a vertical central section of the monolithic part of the composite column, the upper portion of the column and lamps thereon being in elevation; Fig. 4 is a fragmentary vertical central section of the upper portion of the lamp structure on an enlarged scale; and Fig. 5 is a section on the line V—V in Fig. 3.

Similar reference characters in the different figures of the drawings indicate corresponding or like elements or features of construction herein referred to in detail.

In Fig. 1 the numeral 1 indicates a table, 2 the new stand lamp generally, and 3 the lamp shade commonly used on stand lamps, illustrating the general character of the invention and the purposes thereof.

A practical embodiment of the invention comprises a broad base having a suitable bottom 4 and a side face or faces 5, and also an inclined top face 6, the bottom of the base preferably having a thin cushioning pad 7 thereon composed of felt or other suitable material. A tapered column 8 is supported upon the base and preferably is integral therewith, the base and the column being of monolithic formation composed of cement 9 as a body in which are embedded many fragments of broken marble or other substance capable of being ground and polished, there being many differently shaped and differently colored face stones 10 and 11 in the face of the column, more or less similar face stones 12 in the side faces of the base and in the inclined top face of the base. Other fragments of marble or stone 13 are entirely embedded in their rough state in the column and its base. The column and the base may have any desired external contour, and the face or various face portions of the concrete body are on one and the same plane with the face portions of the fragments, all being smooth and polished to such a degree as the different portions are capable of being polished after having been ground smooth.

A metallic tube comprising a straight main portion 14 is embedded centrally in the column and extends upward a suitable distance beyond the top of the column and constitutes a shaft portion of the column, the

tube having a curved portion 15 and a horizontal portion 16 embedded in the base. The top of the monolithic portion of the column is provided with a metallic cap comprising a collar 17 having a flange 18 seated upon the top of the column portion and rigidly secured thereto by means of rods 19 and 19' embedded in the cement and extending through the flange, each rod having a head 20 thereon engaging the top of the flange. A hollow stem 21 is provided which is slipped over the projecting portion of the tube 14 and has an attachment portion 22 which is secured in the flange 17, preferably by means of screw threads, the collar being larger internally than the external diameter of the tube 14. The stem has a hollow head on its top adapted for supporting suitable lamps or the burners of such type as may be desired; for electric lighting there being a hollow head portion or shell 23 connected with a nut 24 which is secured, preferably by means of screw threads, to the stem 21, a standard 25 being arranged in the shell and having a foot 26 that is secured also to the stem to fasten the shell thereto, the standard having an arm 27 on its top supporting a screw 28 that extends through a cap plate 29 fitted to the top of the shell and secured in place by means of a nut 30 placed on the screw. When a lamp shade is desired the necessary shade holder may be placed on the cap plate 29 and secured in place by the nut 30, as will be understood. A suitable number of switch boxes 31, 31' are connected to the shell and have electrical lamp sockets 32, 32' into which electrical lamps 33, 33' are secured.

In order to supply the lamps with electrical current an electrical circuit cord 34 is arranged in the tube within the column and is provided on its outer end with a conventional plug 35 to be connected with any suitably arranged electrical socket. The circuit cord 34 extends upward beyond the tube 14 and into the casing 23, the circuit wires being suitably connected with the switch boxes as in common practice.

The monolithic column structure has novel reinforcing rods therein comprising main portions 36, 36' extending from the base upwardly at an inclination and convergently to a portion of the tube 14, each rod preferably having a foot portion 37 extending outwardly in the base of the column; and the rods have upwardly extending upper portions 38, 38', diverging from the tube 14. A band 39 extends about the rods where they are in contact with the tube and secures the rods to the tube.

The body portion of the monolithic column structure is composed of Portland cement or similar cement and crushed substances, preferably marble of different

colors, or crushed "sea shells," providing irregularly shaped particles which are mixed with the cement to form a mass of suitable consistency. The mass is moulded in a suitable form. The surface of the monolithic column and its base are suitably ground when hardened and made smooth, after which the surfaces are suitably polished, the exposed faces of the marble or other particles becoming highly polished, while the cement portions of the surfaces become only slightly polished and form pleasing background for the highly polished and differently colored spots thereon formed by the faces of the fragments embedded in the cement.

It should be understood that the hollow head of the stem 21 may be of such construction as to distribute gas to burners connected therewith, and that illuminating gas may be suitably conducted into the horizontal portion 16 of the tube.

In practical use the bottom of the base of the column is placed where desired and may readily be transferred to other positions. The plug 35 is connected with a socket as usual, and the lamps may be supplied with electric current in the customary manner, by operation of the electrical switches in the switch boxes. When the lamps are in operation, light rays therefrom project downwardly in slanting directions on the surfaces of the column, the highly polished surfaces or the spots in the surfaces reflecting or deflecting the light rays with pleasing effects.

Having thus described the invention, what is claimed as new is,—

1. An art stand lamp including a base, a tapered column upon the base, a cap secured to the top of the column, a hollow stem secured to the cap, a hollow head secured to the stem to support a lamp, a tube extending through the base and the column and also into the stem and nearly to the top of the stem, and rods arranged in the column and extending into the base and also upward nearly to the cap.

2. An art stand lamp including a base, a tapered column upon the base, a cap arranged upon the top of the column, securing devices embedded in the column and engaging the cap to secure it in place, a hollow stem secured to the cap, a hollow head secured to the stem to support a lamp, a tube extending through the base and the column and also into and nearly to the top of the stem, and rods arranged in the column about the tube and extending into the base and also upward nearly to the cap and between the securing devices.

3. An art stand lamp including a base and a tapered column integrally connected together and having irregular particles therein, some of the particles being embedded partially in the base and partially in the

column, a cap secured to the top of the column, a hollow stem secured to the cap, a hollow head secured to the stem to support a lamp, a tube extending through the base 5 and the column and also into and nearly to the top of the stem, and rods arranged in the column about the tube and extending into the base and also nearly to the cap, the rods being arranged among the irregular 10 particles in the base and the column.

4. An art stand lamp including a base, a tapered column upon the base, a cap secured to the top of the column, a hollow stem secured in the cap, a hollow head secured to the stem, electrical switch boxes connected 15 to the head, a tube extending through the

base and the column and also through the cap and into the stem and nearly to the top of the stem, an electrical circuit cord extending through the tube and the head and 20 into the switch boxes, rods arranged in the column and extending into the base, each rod extending upward from the base at an inclination to the tube and thence divergently from the tube, and a band embracing 25 the rods and securing them to the tube.

In testimony whereof, I affix my signature in presence of two witnesses.
